UNITED STATES PATENT OFFICE.

ARCHIBALD F. REDDIE, OF PHILADELPHIA, PENNSYLVANIA, ASSIGNOR TO McCALLUM & McCALLUM, OF SAME PLACE.

DESIGN FOR CARPET.

SPECIFICATION forming part of Design No. 25,298, dated March 24, 1896.

Application filed February 24, 1896. Serial No. 580,531. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for a Carpet or other Fabric, of which the following, taken in connection with the accompanying drawing, is a specification.

My design comprises the pattern which is illustrated in the accompanying drawing and which imparts when displayed upon a fabric a distinguishing or characteristic appearance.

In the drawing, A is the body, B the border, and A and B the carpet.

The leading or characteristic feature of the pattern may be said to be the corniform figure a, displayed upon a background b.

Obviously the design of my invention may be applied to Wilton, Brussels, velvet, and other carpets, and it may also be presented in a variety of colors or combinations of colors.

What I claim as new, and desire to secure by Letters Patent, is—

1. In the design for a carpet the body A, substantially as shown.

2. In a design for a carpet the border B, substantially as shown.

3. The design for a carpet consisting of the body A, and the border B, substantially as shown.

In testimony whereof I have hereunto signed my name in the presence of two witnesses.

ARCHIBALD F. REDDIE.
